UNITED STATES PATENT OFFICE.

OLGA BERGHORN, OF JERSEY CITY, NEW JERSEY.

CIGARETTE-BOX.

1,116,372.

Specification of Letters Patent. Patented Nov. 10, 1914.

Application filed November 12, 1913. Serial No. 800,451.

To all whom it may concern:

Be it known that I, OLGA BERGHORN, a citizen of the United States, and a resident of Jersey City Heights, Jersey City, in the 5 county of Hudson and State of New Jersey, have invented certain new and useful Improvements in Cigarette-Boxes, of which the following is a specification.

My invention is an improved cardboard 10 cigarette box or carton provided, in a separate compartment, with a supply of matches for lighting the contained cigarettes.

The object is to provide a construction which is simple, neat, strong and effective 15 and which will not add materially to the cost of the box; and, while constituting an attractive novelty, will have the general appearance of the ordinary hinged-cover form of cigarette box with which the public is 20 familiar.

Briefly and generally described, the device comprises an ordinary or suitable form of cigarette box having a hinged closure for retaining the cigarettes, a strip of matches 25 and igniting material applied to the top of this closure, a false lid of stiff cardboard, of the same size as the top of the closure, to overlie the matches, and a strip applied to the top of the box closure and the inside of 30 the false lid so as to constitute an internal hinge member, and in addition covering the outside of the false lid and extended around the box so as to constitute external hinge members. In this way a strong construction 35 and neat appearance are secured in a very economical manner.

In the accompanying drawings illustrating the invention: Figure 1 is a vertical section through the device, showing the false 40 lid raised; Fig. 2 is a perspective view thereof, looking at the back of the box and the top of the false lid, which is partly closed; Fig. 3 is a vertical section through a modified construction, showing both the closure 45 and the false lid open; Fig. 4 is a plan view of Fig. 3 with the closure down and the false lid entirely opened; and Fig. 5 is a side elevation of an embodiment of the invention with the false lid closed and showing how 50 this lid may be provided with a permanent curvature so as to lie closely against the top of the box.

The box proper is of the type consisting of a body or tray 10 to hold the cigarettes and 55 a closure 11 hinged to the back of the body at 14. A false lid 12 is hinged to the back

of the closure and is of the same size and shape as the top thereof, being formed of a rectangular piece of cardboard, preferably of about the same weight as the stock of 60 which the body and closure are made.

The hinge connecting the false lid 12 with the closure includes an inner flexible sheet-hinge member 13, which is preferably in the form of a paper folder consisting of two 65 leaves 15 and 16, the leaf 15 covering the inner surface of the lid 12 and being pasted or otherwise united thereto, while the leaf 16 is similarly applied to the top of the closure 11. A strip or series of matches 17, 70 with a strip of paper 18 bearing igniting composition 19, are secured to the upper surface of the leaf 16, and are thus carried by the closure 11.

The strips forming the folder 13 passes 75 over the edge of the false lid 12 and covers and is pasted to the upper surface of the lid 12, forming a label strip 20, and extends down and is pasted to the back of the box proper and preferably also around beneath, 80 so as to cover the bottom of the same. By this construction this label strip also forms the hinge 14 between the closure 11 and the body 10.

The label strip, as its name indicates, is a 85 strip of paper which is printed or lithographed with the label, trade-mark, or other display matter of the particular cigarette manufacturer or dealer. By extending continuously over the outer surfaces of the 90 false lid and box proper, it affords a neat and economical construction; and, together with the folder 13, constitutes a strong, though entirely flexible, hinge for the false lid. The leaf 15 also constitutes a display 95 surface adapted to bear advertising or other matter.

As shown in Fig. 5, the comparatively stiff material of the false lid enables it to be given a permanent upward curvature from 100 front to back, to assist the false lid in lying substantially flat on top of the cover without the employment of any special fastening means. The dotted lines 21 in this view indicate that both the false lid and the closure 105 may be held closed by the Internal Revenue stamp or other seal prior to the breaking of the package.

What I claim as new is:

A cardboard cigarette box having a body 110 and a hinged closure bearing matches and igniting material on top, in combination

with a false cardboard lid hinged to the rear edge of said closure to cover the top of the same with its matches and igniting material, and a continuous display and label strip applied to the top of the main closure, the inner and outer surfaces of the false lid and extending around the outside of the box proper and thus affording inner and outer hinge members connecting said false lid to

said closure and also forming a hinge between the main closure and the box body.

In witness whereof I have signed my name in the presence of two subscribing witnesses.

OLGA BERGHORN.
